CASING FOR AN ELECTRIC DRILL

Filed Dec. 6, 1928

*Inventor:
John J. Holloway
by G. Gray Lindsey
Attest.*

UNITED STATES PATENT OFFICE.

JOHN J. HOLLOWAY, OF NEW BRITAIN, CONNECTICUT, ASSIGNOR TO THE STANLEY WORKS, OF NEW BRITAIN, CONNECTICUT, A CORPORATION OF CONNECTICUT.

DESIGN FOR A CASING FOR AN ELECTRIC DRILL.

Application filed December 6, 1928. Serial No. 29,138. Term of patent 14 years.

To all whom it may concern:

Be it known that I, JOHN J. HOLLOWAY, a citizen of the United States, and a resident of New Britain, in the county of Hartford, State of Connecticut, have invented a new, original, and ornamental Design for Casing for an Electric Drill, of which the following is a specification, reference being had to the

accompanying drawing, forming part hereof.

In the accompanying drawing, the figure is a perspective view of a casing for an electric drill showing my design.

I claim:

The ornamental design for a casing for an electric drill, as shown.

JOHN J. HOLLOWAY.
